UNITED STATES PATENT OFFICE

145,653

DESIGN FOR A COMBINED COASTER AND ASH TRAY HOLDER

Leo J. Binder, Spokane, Wash.

Application August 3, 1945, Serial No. 121,192

Term of patent 14 years

(Cl. D85—2)

To all whom it may concern:

Be it known that I, Leo J. Binder, a citizen of the United States, residing at Spokane, in Spokane County and State of Washington, have invented a new, original, and ornamental Design for a Combined Coaster and Ash Tray Holder.

Figure 1 is a perspective view of a combined

coaster and ash tray holder showing my new design;

Figure 2 is a side elevation thereof.

I claim:

The ornamental design for a combined coaster and ash tray holder, as shown.

LEO J. BINDER.
